UNITED STATES PATENT OFFICE.

CARL J. LJUNGGREN, OF PROVIDENCE, RHODE ISLAND.

HYGIENIC CHALICE.

1,028,752.

Specification of Letters Patent.

Patented June 4, 1912.

Original application filed January 23, 1907, Serial No. 353,725. Divided and this application filed October 10, 1908. Serial No. 457,157.

To all whom it may concern:

Be it known that I, CARL JULIUS LJUNGGREN, a subject of the King of Sweden, residing at Providence, in the county of Providence and State of Rhode Island, have invented certain new and useful Improvements in Hygienic Chalices, of which the following is a specification.

My invention relates to an improvement 10 in hygienic chalices, which forms a divisional application of my application filed January 23, 1907, bearing Serial No. 353,725, on hygienic communion chalices, the object being to provide means for delivering a 15 certain quantity of the liquid to the communicant when the chalice is tilted, and to provide a receptacle to receive the waste liquid which is not consumed by the person drinking from the chalice. The waste 20 liquid is received in a receptacle, which discharges it, upon the tilting of the chalice, into another receptacle, which prevents its return to the drinking edge of the cup.

The invention consists of many novel features of construction and combinations of parts which will be hereinafter described and more fully pointed out in the claims.

In the accompanying drawings—Figure 1 is a vertical sectional view; Fig. 2 is a 30 top plan view with certain portions broken away to show the interior constructions; and Fig. 3 is a sectional view of the modified form.

A represents the chalice or cup, which is 35 provided with a hollow leg 2, and formed at the base of the leg is a waste chamber 3. A flange 1 extends inwardly from the drinking edge of the cup. Connected to the lower edge of the flange are ribs or spokes 40 4, which are brought together at their lower ends. Spaces are formed between the spokes for the waste wine to pass through, and the ribs afford means for conducting the liquid from the flange downwardly.

A reservoir 5 is received within the cup or chalice and below the flange and ribs. The reservoir is provided with a hollow tubular extension 6, which is received in the leg 2 of the chalice and supports the reservoir 50 within the chalice. The reservoir is so supported within the chalice that a space is formed between the reservoir and the chalice, and openings 7 are formed in the tubular extension to permit the waste liquid 55 to pass from the chalice down into the waste

chamber 3. An outlet chamber 8 is received in the chalice and is supported above the ribs by a tube 9, which extends through the upper wall of the reservoir and through the lower ends of the spokes. An inlet chamber 10 is received in the reservoir 5 and is connected to the outlet chamber by a tube 11, which engages the tube 9. The reservoir is provided with an opening 12, which registers with an opening 13 formed in the flange 1. A tube 14 extends through the opening 13 in the flange into the reservoir through the opening 12, and through this tube 14 a liquid is poured for filling the reservoir. An air vent tube 15 is connected 60 to the tube 11 and extends up to the filling opening 12 for the purpose of admitting air to the pipe 10 which conducts the liquid from the inlet chamber to the outlet chamber, and thereby preventing siphoning and 65 discharging only a measured quantity of the liquid from the inlet chamber to the outlet chamber. The outlet chamber 8 is provided with a cover 16, which is provided with an opening 17 to permit of the liquid passing 70 from the outlet chamber onto the flange 1.

The top of the reservoir is hollow or approximately cup shape forming the drain pocket or chamber 18.

In delivering the liquid from the reservoir 85 to the outlet chamber the chalice or cup is tilted until the inlet chamber 10 receives a certain quantity of wine or liquid permitting a certain quantity of the liquid to pass from the reservoir into the outlet chamber, 90 where it is dispensed onto the flange 1. When the chalice is brought to an upright position if any of the liquid which is passed from the outlet chamber onto the flange has not been consumed it will flow down the 95 flange through the openings between the ribs or spokes into the drain pocket 18, the spokes assisting in conducting the liquid from the flange as they are slightly depressed from the lower edge of the flange. 100 When the chalice is again tilted to permit of the liquid passing from the reservoir to the inlet chamber, and from the inlet chamber to the outlet chamber, the waste wine which has collected in the drain pocket will pass 105 from the drain pocket into the space formed between the lower portion of the reservoir and the chalice and then passing through the openings 7 into the leg 2 and down into the waste chamber 3. 110

In the modification shown in Fig. 3 the structure is the same with the exception that the ribs 4 are done away with and the outlet chamber 8 is seated upon the upper portion 5 of the reservoir. A ball valve 19 is formed in the inlet chamber for admitting a certain quantity of the liquid from the inlet chamber to the outlet chamber.

It is evident that more or less slight 10 changes might be made in the form and arrangement of the several parts described without departing from the spirit and scope of my invention, and hence I do not wish to be limited to the exact construction herein 15 set forth; but:—

Having fully described my invention, what I claim as new and desire to secure by Letters Patent is:—

1. A chalice comprising an outlet chamber, a reservoir connected to the outlet chamber whereby a measured quantity of liquid will be discharged into the outlet chamber when the reservoir is tilted, and then righted, and a drain pocket formed between the outlet chamber and reservoir.

2. A chalice comprising an outlet chamber, a reservoir connected to the outlet chamber whereby a measured quantity of liquid will be discharged into the outlet chamber when the reservoir is tilted, and then righted, a drain pocket formed between the outlet chamber and reservoir, a waste chamber, and means for conducting the waste liquid from the drain pocket to the waste chamber.

3. A chalice comprising a cup, a reservoir mounted within the cup, said reservoir and cup having a space therebetween, an outlet chamber mounted upon and connected with the reservoir, whereby a measured quantity of liquid will be discharged into the outlet chamber when the cup is tilted and then brought to an upright position, and a drain pocket formed between the outlet chamber

and reservoir for receiving the waste liquid 45 from the drinking edge of the cup.

4. A chalice comprising an outlet chamber, a reservoir, an inlet chamber in the reservoir connected to the outlet chamber for delivering the liquid from the reservoir to 50 the outlet chamber, and a drain pocket formed between the outlet chamber and reservoir.

5. A chalice comprising an outlet chamber, a reservoir connected with the outlet 55 chamber, an inlet chamber in the reservoir connected to the outlet chamber, and an air vent tube in communication with the inlet chamber.

6. A chalice comprising an outlet chamber, a reservoir for supporting the outlet chamber, an inlet chamber, a tube connecting the inlet chamber and outlet chamber, and an air vent tube connected to the first named tube.

7. A chalice comprising an outlet chamber, an inwardly extending flange connected to the chalice, a reservoir, an inlet chamber connected with the reservoir, means connecting the inlet chamber and outlet chamber, a 70 drain pocket formed between the outlet chamber and inlet chamber to receive the waste liquid.

8. A chalice comprising a cup, a reservoir mounted within the cup having a space separating the reservoir from the cup, a concave cover mounted upon the reservoir forming a drain pocket, and an outlet chamber mounted upon the reservoir, and connected with the reservoir, whereby a measured quantity of liquid may be discharged from the reservoir to the outlet chamber.

In testimony whereof I affix my signature, in the presence of two witnesses.

CARL J. LJUNGGREN.
